UNITED STATES PATENT OFFICE

LEE H. HOOK, PERCY EVANS, AND CHARLES S. WALLRAB, OF CHICAGO HEIGHTS, ILLINOIS, ASSIGNORS TO CALUMET STEEL COMPANY, OF CHICAGO, ILLINOIS, A CORPORATION OF ILLINOIS

REPEATER

Application filed May 3, 1928. Serial No. 274,800.

This invention relates to improvements in loop return repeaters for rolling mills and more particularly for repeaters for single sets of three-high rolls.

5 One object of our invention is to provide a simple and efficient repeater which may be readily and easily applied to a set of three-high rolls and which when applied will automatically guide and return the bar being 10 rolled from one pass between the rolls to another, without any manual lifting or manipulation of the bar as heretofore.

Another object of our invention is to provide a repeater which will positively and accurately guide and direct the outcoming forward end of the bar from one pass to another without any opportunity afforded for the free forward end of the bar being displaced out of the repeater and running wild.

20 A further object of our invention is to so make the repeater that the loop formed in the bar may readily leave the repeater and extend outward and backward to the extent necessary by the differential feed on the bar 25 where it is engaged by the rolls at the passes therein.

A further object of our invention is to make the arc of the repeater on such a radius that the tail end of the bar when it leaves 30 the pass between the rolls will follow easily around the repeater without being displaced out of the same to have a whipping action and endanger the workmen about the mill.

The invention consists further in the matters hereinafter described and claimed.

In the accompanying drawings—

Fig. 1 is a vertical sectional view through the set of three-high rolls and showing the repeater of our invention applied thereto.

40 Fig. 2 is an end view of the repeater; and Fig. 3 is a top plan view of the same.

In the drawings, 1, 2, and 3 indicate the vertically arranged, horizontally disposed rolls of a three-high mill. The ends of the 45 rolls are journaled and supported in upright standards 4 at the opposite ends of the rolls, as in mill design. The billet being rolled is introduced manually back and forth into the first passes between the rolls until the last 50 passes where the repeater of our invention

takes care of the reduced bar and automatically guides it from the next to the last pass into the last pass without any manual lifting or manipulation, as heretofore.

The repeater has a receiving section 5 and a delivery section 6. The receiving section 5 is made in the form of an upwardly opening trough having upright side walls 7, 8 and a bottom wall 9. The repeater is arranged on the rear side of the rolls 1 to 3 with the entrance end of the repeater in line 55 with the desired pass between the upper and the intermediate rolls 1, 2 so as to receive the bar therefrom. A plate 10 secured to the entrance end of the trough 5 overlaps and is secured by bolts 11, 11 to a horizontal plate 12 which extends between and is attached by bolts 13 to the standards 4. In this manner, the entrance end of the trough 5 is supported 60 in position opposite the desired pass between the rolls. Guide blocks 15, 15 are secured to the plate 12 between the rolls and the trough for guiding the free end of the bar as it leaves the rolls into the trough 5. At the entrance 65 end of the trough, its outer side wall 7 is flared outward, as at a, so as to insure a guiding of the free end of the bar into the trough as the free end of the bar leaves the guide blocks 15, 15. On the front side of the rolls, are guide-blocks 16, 16 bolted to and supported by a plate 17 also extending between 70 and bolted to the standards 4, 4, as shown in Fig. 1.

The trough 5 where it extends outward from the plate 12 is substantially straight and horizontal, so as to be in the general path of the outward projection of the bar from the rolls 1, 2. The straight portion of the trough guides the free outer end of the bar into the loop return section 18 of the trough at the 75 outer end of the repeater. The radius or curvature of this section 18 is such that the free end of the bar will easily follow around the curve and will not, under ordinary circumstances, jump out of the trough and run wild.

The loop section 18 inclines downward toward the rolls 2, 3 and the outlet end b of the section 18 is lower than the horizontal trough-section 5. The outlet end b communicates 80 85 90 95 100

with the delivery section 6 of the repeater by having a telescopic connection therewith, as shown in Fig. 3. The section 6 is in the form of an elongated tubular spout and extends at 5 an inclination downward toward the last pass between the intermediate roll 2 and the lower roll 3. The outlet end of the section 6 is supported at the elevation desired by bolts 19, 19 arranged above and below the spout and 10 extending through holes 20 in the uprights 21, 21 of a U-shaped bracket which is secured by a bolt 22 to a cross-plate 23 extending between and fastened to the standards 4. The holes 20 in the uprights 21 are vertically 15 arranged to permit vertical adjustment of the outlet end of the section 6. The bolt 22 may extend through an elongated slot in the plate 23 to allow for lateral adjustment of the outlet end of the spout 6 so that it may be 20 properly aligned with any one of the desired passes between the rolls 2, 3. This is also permitted by reason of the flexible connection between the spout 6 and the trough 5 at b.

The outlet end of the spout 6 extends into 25 the passage in the guide casting 24 which is bolted to the plate 23 between the rolls 2, 3 and the spout 6, as shown.

The free end of the bar on entering the pass between the intermediate and lower rolls 2, 3 30 is gripped by said rolls, and the bar is further reduced due to the shape of the pass. This reduction in the metal between the rolls 2, 3 will retard the feed of the bar at said rolls to less than the feed on the bar at the rolls 1, 2. The result is that the difference in 35 the feed on the bar will cause the loop c in the bar to elongate rearwardly and leave the trough 5. The trough being open allows this to happen and permits the elongated loop to 40 extend back beyond the repeater over the upper edge of the outer side wall 7 of the trough to the extent required for the loop to compensate for the differential feed on the bar at the respective passes between the rolls.

45 As soon as the rear or tail end of the bar leaves the grip of the rolls 1, 2, the bar is then subjected only to the feed of the rolls 2, 3, and the extended loop in the bar will be rapidly taken up. This brings the bar back into the 50 trough, and the rear or tail end of the bar follows along the trough without any chance to whip out of the same. The inner side wall 8 of the trough around the loop section 18, as at d, is made higher than the front wall 55 7 so that the extended loop in being rapidly taken up can not be drawn inward out of the repeater to do damage to the repeater or to the bar or to foul in the mill.

The trough section 5 is housed at 25 from 60 its outlet end b to approximately the center of the curve of the loop section 18. The housing 28 has an exceedingly wide mouth at the curve so that the extended loop c may form without interference. The enclosing walls of 65 the housing 25 also act as a guard for the tail

end of the bar as it leaves the curve and prevents said end from whipping out of the guide as it leaves the curve at 18. The wall 7 extends into the housing 25 so as to guide the forward or advancing end of the bar into the delivery spout 6. As shown in Fig. 2, the wall 7 terminates short of the top of the housing 25, so that the loop may readily pass over the same both when forming and when being taken up.

70 With the repeater extending rearward of the mill, the repeater lies practically outside of the mill and we provide a support for it at its outer or curved end. The form of support shown comprises a vertically disposed leg 26 having at its lower end an adjusting screw 27 which bears against the floor on the rear side of the mill for supporting the rear end of the repeater at the elevation desired.

75 The device of our invention is simple in construction and makes an effective repeater for a single set of three-high rolls. It may be readily and easily applied to the mill and guides the bar from a pass between the upper and intermediate rolls of the mill to a pass between the intermediate and lower rolls of the same mill, thereby doing mechanically and automatically the work which has heretofore been manually done. The repeater saves considerable time because the forward end of the bar is directed back into the lower pass within a short time after the bar has been projected from the upper pass, instead of waiting until the entire bar has 80 passed through the upper pass before it is introduced in the lower pass, as under a manual operation. The repeater also saves expense because a workman is not required for the passes which the repeater serves. With 85 the trough and delivery sections 5, 6 made separate, they may be cheaply made of castings, and moreover the delivery part may have a flexible connection with the trough part for both vertical and horizontal adjustments.

90 We do not wish to be limited to the use of the repeater at any particular passes of rolls nor to the details of structure shown and described, as these may be variously changed and modified without departing from the spirit and scope of our invention.

115 We claim as our invention:

1. A rolling mill repeater, comprising a receiving portion with a loop return section, and a delivery portion in communication with said loop return section, said receiving portion being in the form of an upwardly opening trough having inner and outer side walls, 120 said trough having a housing section where the trough enters the delivery portion, with the outer side wall of the trough extending into said housing and terminating short of the top of the same.

125 2. A rolling mill repeater, comprising a

receiving portion with a loop return section, and a delivery portion in communication with said loop return section, said receiving portion being in the form of an upwardly open-
5 ing trough having inner and outer side walls, said trough having a housing section where the trough enters the delivery portion, said housing having a flared open outer end and the outer side wall of the trough extending
10 into said housing approximately at the center of the same.

3. In a rolling mill, in combination, a set of vertically disposed rolls, a pair of supports disposed at different vertical elevations
15 on one side of the rolls in outward spaced relation thereto and arranged with one support for the pass between an upper roll and the next roll therebelow, and the other support for the pass between the lower roll and the next roll
20 thereabove, a repeater device on the same side of the rolls as the supports and arranged beyond the same, said repeater device comprising two parts only, one part forming a receiving portion and having a loop return section with the entrance end of the receiving portion mounted on the upper support to receive the work from the rolls opposite such support, the other part of the repeater device forming the delivery portion of the repeater
25 and having a telescopic fit at one end with the loop return section and mounted at the other end on the lower support to deliver the work to the rolls opposite the same, guide means for the work between the supports and the rolls opposite which they are respectively arranged, and a support for the portion of the repeater device beyond the mill.

4. In a rolling mill, in combination, a set of three-high rolls, a pair of supports disposed at different vertical elevations on one side of the rolls in outward spaced relation thereto and arranged with one support for the pass between the upper and the intermediate rolls and the other support for the pass be-
40 tween the intermediate and the lower rolls, a repeater device on the same side of the rolls as the supports and arranged beyond the same, said repeater device comprising two parts only, one part forming a receiving portion and being in the form of an upwardly open-
45 ing trough with a loop return section with the entrance end of the trough mounted on the upper support to receive the work from the rolls opposite such support, the other part of the repeater device forming a delivery portion therefor and being in the form of a tubu-
50 lar spout, having a telescopic fit at one end with the loop return section and the other end mounted on the lower support to deliver the work to the rolls opposite the same, guide means for the work between the supports and the rolls opposite which the supports are re-
55 spectively arranged, and a support for the portion of the repeater device beyond the mill.
60
65 the receiving portion of the repeater device

extending substantially horizontally outward from the upper support, and the loop return section and the delivery spout being downwardly inclined toward the lower support.

5. In a rolling mill, in combination, a set of three-high rolls, a pair of supports disposed at different vertical elevations on one side of the rolls in outward spaced relation thereto and arranged with one support for the pass between the upper and the intermediate rolls and the other support for the pass between the intermediate and the lower rolls, a repeater device on the same side of the rolls as the supports and arranged beyond the same, said repeater device comprising two parts only, one part forming a receiving portion, and having an integrally connected loop return section with the entrance end of the receiving portion mounted on the upper support to receive the work from the rolls opposite such support, the other part of the repeater device forming a delivery portion therefor and being in the form of a tubular spout having one end connected with the loop return section and the other end mounted on the lower support to deliver the work to the rolls opposite the same, guide means for the work between the supports and the rolls opposite which the supports are respectively arranged, and a support for the portion of the repeater device beyond the mill, the receiving portion of the repeater device extending substantially horizontally outward from the upper support and being open on its upper side so that the loop formed in the work when engaged by both rolls may extend out of the repeater, the loop return section being in the form of a housing, and the latter and the spout being downwardly inclined toward the lower support.

In testimony whereof we affix our signatures.
